(57) **CLAIM**

The ornamental design for a bucket lid seat, as shown and described.

DESCRIPTION

FIG. 1 shows the top, front, right side perspective view of an ornamental design of a bucket lid seat according to the invention.

FIG. 2 shows the bottom, back, left side perspective view thereof.

FIG. 3 shows the top plan view thereof.

FIG. 4 shows the bottom plan view thereof; and,

FIG. 5 shows the right side elevation view thereof, the left side, front, and back elevation views being identical images thereof.

Shading lines are used to show solid structures and are not intended to indicate surface decoration.

1 Claim, 4 Drawing Sheets
